UNITED STATES PATENT OFFICE

2,520,818

RECEPTACLE SUPPORT

Charles W. Terry, Tulsa, Okla.

Application December 4, 1947, Serial No. 789,577

1 Claim. (Cl. 248—156)

1

The invention relates to receptacle supports, and particularly to supports for supporting tumblers and bottles on the upper end of a stake, which stake may be forced into the ground adjacent chairs or the like, in gardens and on lawns, so that drinks of various kinds will be supported within easy reach of the occupant of the chair.

A further object is to provide the upper end of the stake with a glass or bottle holding member formed from a plurality of wire convolutions in spaced relation so that condensate on the outer surface of the bottle or glass will not be accumulated within the device.

A further object is to form the lower end of the receptacle holding member from coils in the same plane, to form a bottom for the holder in which condensate will not collect.

A further object is to provide flexibility to the parts of the holder and stake so there will be a limited amount of flexing of the parts when the glass is placed in the device, which will have an agitating effect upon the contents of the glass.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawing:

Figure 1 is a perspective view of the receptacle support.

Figure 2 is a side elevation of the support, showing a glass therein.

Figure 3 is a view similar to Figure 2, but showing a bottle in the support.

Figure 4 is a top plan view of the support.

Referring to the drawing, the numeral 1 designates the stake, adapted to be forced into the ground 2, adjacent a chair or seat. The upper end of the stake terminates in a plurality of horizontally disposed convolutions 3, to form the bottom of the receptacle holder. It will be noted that any condensation which collects on the outside of a glass 4 or bottle 5, will flow downwardly and onto the ground, hence it will not collect in the device, a common difficulty in a solid bottom device.

The outer convolution 3 terminates in an upwardly spiral body 6 having its convolutions in spaced relation so air will circulate around the receptacle, and at the same time, condensation,

2

from iced drinks will flow downwardly and reach the ground.

When the receptacle 4 is placed in the holder convolutions 6 the bottom of the receptacle engages the convolutions and is jogged over each convolution in a manner whereby there is an agitation of the contents of the glass, and as the device, as a whole, is formed from semi-rigid wire it is obvious there is a slight movement or flexing of the stake 1, which will additionally agitate the iced drink within the glass. This flexibility also prevents injury to persons walking around the lawn, which would not be the case were a rigid stake used.

Referring to Figure 4, it will be seen that the holder tapers in diameter towards its lower end, hence it will be seen that as the glass is placed in the holder its bottom edge will jog from convolution to convolution, thereby agitating the contents of the glass.

From the above it will be seen that a glass holder is provided, particularly adapted to use on lawns; formed from a single piece of wire twisted to form and includes an agitating feature.

The invention having been set forth what is claimed as new and useful is:

A glass holder adapted to be used on lawns, said glass holder being formed from a single piece of wire and comprising a stake portion and a glass receiving portion, said stake portion being on the axis of the glass receiving portion, the upper end of the stake terminating in a plurality of spiral convolutions in a horizontal plane and increasing in diameter from the center of the stake outwardly thereby forming a bottom for the glass receptacle, the outer convolution of the bottom terminating in an upwardly spiral body increasing in diameter from the bottom upwardly.

CHARLES W. TERRY.
